UNITED STATES PATENT OFFICE.

JOHN S. BRENNAN, OF MILWAUKEE, WISCONSIN.

AUTOMATIC DAMPER CONTROL.

1,251,633.

Specification of Letters Patent.

Patented Jan. 1, 1918.

Application filed March 6, 1917. Serial No. 152,558.

To all whom it may concern:

Be it known that I, JOHN S. BRENNAN, a citizen of the United States, and resident of Milwaukee, in the county of Milwaukee and

60

5 State of Wisconsin, have invented certain new and useful Improvements in Automatic Damper Controls; and I do hereby declare that the following is a full, clear, and exact description thereof.

10 My invention relates to new and useful improvements in devices for automatically controlling the furnace dampers of vapor heating systems, and is more particularly directed to the provision of a device includ- 15 ing a storage tank, a lever carried actuating tank connected with the storage tank, and connections between the lever and dampers, whereby upon an increase of pressure in the system, water will be driven from the stor- 20 age tank into the actuating tank to procure a rocking movement of the lever, and consequent actuation of the dampers.

It is in general the object of my invention to simplify the structure and increase the 25 efficiency of devices of this character.

It is more particularly an object to pro- 30 vide an exceedingly simple and economically constructed swivel joint between the storage tank and its means of communica-

35 tion with the actuating tank.

It is further an object in this connection to provide an arrangement whereby access of steam to points immediately adjacent the swivel connection is prevented, to thus prevent possible swelling and consequent binding of the connection due to excessive heat imparted thereto.

40 A still further object resides in the provision of a single means of communication between the storage tank and the main heating system which provides for continuous maintenance of vapor pressure in the tank and which also provides for drainage of the tank due to condensation of vapor therein, 45 to maintain a constant level in the tank.

As in most devices of this character, I provide a common connection between the draft damper of the furnace, and a check damper in the chimney flue thereof, and it 50 is further an object of my invention to provide a means for adjusting the connection between said lever and dampers, whereby the relative operation of said dampers may be varied.

55 With the above and other objects and advantages in view, the invention resides more

particularly in the novel combination, for- mation and arrangement of parts herein- after described and pointed out in the ap- pended claims.

60

In the drawings:

Figure 1 is an elevational view of a preferred embodiment of my damper controlling device, showing the draft and check dampers of a furnace diagrammatically as- 65 sociated therewith.

Fig. 2 is a vertical sectional view through the storage tank of my device on the line 2—2 of Fig. 1.

Referring now more particularly to the 70 accompanying drawings, my device comprises a main or storage tank 5 closed at its top and provided with an intermediate partition 6 extending from its closed top to a point adjacent its bottom and dividing the 75 tank into communicating compartments A and B. Communicating with and extending from the compartment B is a pipe 7 which extends to a steam pipe 7^a of the heating sys- 80 tem, or to any other vapor space thereof, such as the top of the boiler. This pipe may be disposed either horizontally as shown, or it may incline downwardly where- 85 by in both instances to provide a free drain- age for the tank, and also provide for a free communication of steam or other vapor 90 with the upper portion of the tank. Formed in the wall of the tank in communication with the compartment A is an opening 8, and projecting outwardly from this opening 90 is a preferably integral nipple 9 having its bore greater than the bore of the opening whereby to form a shoulder in conjunction therewith, and disposed in this nipple is a 95 pivot pipe section 10 having an annular shoulder on its inner end. Mounted on the pivot pipe section and threaded engaged in the nipple is a follower sleeve 11, and packing is disposed between this sleeve and the rib of the pivot pipe section. The outer 100 end of the pivot pipe section is engaged in a T 12 from one end of which a pipe 13 ex- tends to form one arm of the actuating lever of my device, and the outer end of this pipe 13 is threaded into and supports an 105 actuating tank 14. A rod 15 forming the other arm of the lever extends from the other end of the T and carries a preferably conventionally adjustable counter-balancing weight 16.

110 17 designates conventionally a draft damper of a furnace, and 18 designates a check

damper of the chimney flue thereof, and secured to these dampers are chain sections 19 connected by an adjusting plate 20, the chain section of the check damper 18 extending 5 upwardly and about suitable guide pulleys 21 and then downwardly for attachment to the plate and this plate is provided with longitudinal series of apertures for selective engagement of a pin projecting laterally 10 from the intermediate portion of the pipe arm 13 of the lever, and for holding the plate in desired adjusted position with respect to the pin, a spring finger 23 is pivoted to the pipe arm at one end and has its other 15 end notched to receive the pin 22 and to resiliently press against the plate.

A water glass 24 has its ends connected with the top and bottom portions of the compartment B of the storage tank.

20 Taking up now the operation of my device, the device is adjusted so that with the normal desired pressure of the heating system the lever 13—15 is inclined with its tank in a raised position, preferably with 25 the draft damper closed and the check damper partly open. Upon increase of pressure in the system and consequently in the upper portion of the compartment B of the storage tank, water is forced by such pressure into 30 the compartment A and from thence through the pipe 13 into the actuating tank 14, and the pipe arm 13 of the lever becomes consequently weighted sufficiently to swing the lever and open the check damper 35 18, or close the draft damper 17, or actuate both dampers in accordance with the relative positions of the dampers and the degree of operative movement of the lever arm, such actuation of the dampers obviously serving 40 in any instance to check the fire in the furnace and consequently reduce the pressure of the system. Upon such reduction of pressure, the water will flow back into the storage tank and the lever and its connected 45 dampers will move to a position wherein the desired vapor pressure is maintained. By the provision of the plate 20 adjustably connected with the lever arm 13, desired relative adjustments of the draft and check dampers may be most readily effected. It is 50 noted that the volume of the compartment B of the storage tank 5 is equal to the volume of the actuating tank 14. Consequently upon a maximum occurrence of pressure filling the tank 14, the water glass 24 would be 55 practically emptied and thus by these equal volumes, the exact vapor pressure may be read throughout the entire length of the water glass 24, it being noted that as usual 60 in devices of this character the tank 14 normally has free communication with the atmosphere, and may be provided if desired with a conventionally designated valve 25 preferably of the float type to prevent its 65 possible overflow under excessive pressure

conditions. Thus the compartment A of the storage tank 5 is at all times full of water and the access of steam thereto is prevented to thus prevent possible excessive heating of the swivel joint afforded by the nipple 9 and 70 pipe section 10, which might cause a binding of said parts interfering with free pivotal movement of the lever.

Inasmuch as steam or other vapor is at all times disposed in the tank 5, the normal 75 rate of condensation serves to maintain a sufficient supply of fluid therein, and by the utilization of a single pipe communicating with the upper portion of the tank and with the vapor space of the heating system for 80 the drainage of said tank, the possibility of undesired variation of the level of the tank due to unusual conditions in the system is avoided without the use of check valves or other means.

85 What is claimed is:

1. A controlling device of the class described comprising the combination with a boiler of a closed tank communicating at its upper end with the steam space of the boiler, 90 a partition extending from the top of the tank to a point adjacent its bottom, a lever including a pipe arm and a lateral pipe section communicating with the arm and pivoted to and communicating with the 95 upper portion of the tank at the side of the partition opposite its communication with the boiler, a tank carried by and communicating with said pipe arm of the lever and heat control means for the boiler connected 100 with said lever.

2. A controlling device of the class described comprising the combination with a boiler of a closed tank communicating at its upper end with the steam space of the boiler, 105 a partition extending from the top of the tank to a point adjacent its bottom, a lever including a pipe arm and a lateral pipe section communicating with the arm, an annular rib on the free end of said pipe section, a nipple extending from the side of the partition opposite its communication with the boiler and receiving the lateral pipe section, a sleeve on the pipe section threaded 110 engaged with the nipple, packing disposed between the sleeve and annular rib of the pipe section, a tank carried by and communicating with said pipe arm of the lever and heat control means for the boiler connected 115 with said lever.

3. A controlling device of the class described comprising the combination with a boiler of a closed tank communicating at its upper end with the steam space of the boiler, 120 a partition extending from the top of the tank to a point adjacent its bottom, and dividing it into two communicating compartments, a lever including a pipe arm and lateral pipe section communicating with the 125 upper portion of one of the compartments, 130

- means connecting the other compartment with the steam space of the boiler, a tank carried by and communicating with said pipe arm of the lever, the volumes of the 5 tank and the last mentioned compartment being equal, a water glass communicating with the last named compartment, and heat control means for the boiler connected with said lever.
- 10 4. A controlling device of the class described comprising the combination with a boiler of a closed tank, a partition extending from the top of the tank to a point adjacent its bottom whereby to provide two communicating compartments, a pipe connecting the top of one compartment with the steam space of the boiler, a pivot mounted upon the wall of said tank and communicating with the other compartment, a lever swiveled 15 to said pivot and including a pipe arm communicating with said other compartment through the pivot and a rod arm, a counter-balanced weight adjustably carried by the rod arm, a tank carried by and communicating with said pipe arm, the volumes 20 of said tank and the first mentioned compartment being equal, and heat controlled means for the boiler and adjustably connected with said lever, the water of the first mentioned compartment being adapted upon 25 entrance thereto from the boiler of excessive steam pressure to force the water in said other compartment into the tank carried by said lever whereby to operate the heat controlled means, substantially as described. 30
- 15 In testimony that I claim the foregoing I have hereunto set my hand at Milwaukee, in the county of Milwaukee and State of Wisconsin.
- 20 JOHN S. BRENNAN.
